UNITED STATES PATENT OFFICE.

FITCH H. BEACH AND FRED S. BEACH, OF CHARLOTTE, MICHIGAN.

ROAD-DRAG.

No. 884,352.

Specification of Letters Patent.

Patented April 14, 1908.

Application filed May 25, 1907. Serial No. 375,705.

To all whom it may concern:

Be it known that we, FITCH H. BEACH and FRED S. BEACH, citizens of the United States, residing at Charlotte, in the county of Eaton 5 and State of Michigan, have invented a new and useful Road-Drag, of which the following is a specification.

This invention has relation to road drags and it consists in the novel construction and 10 arrangement of its parts as hereinafter shown and described.

The object of the invention is to provide a road drag made up of a series of angular steel blades arranged parallel to each other and 15 gradually decreasing in length from the front blade to the rear blade. A plate is located transversely upon the upper portions of the blades and is riveted to each blade and forms a means for holding the blades together. 20 Said plate is reinforced by angular strips located upon its upper surface and at its ends and which may be used as runners when the implement is turned bottom side up for transportation. A draft chain is attached to 25 the front blade and is provided at intervals with elongated links to which a clevis may be attached for connecting the implement with a single or double tree.

In the accompanying drawing:—Figure 1 30 is a perspective view of the drag, and Fig. 2 is a transverse sectional view of the same.

The drag consists preferably of three blades designated as 1, 2 and 3, although a greater 35 number of blades may be employed, if desired. The said blades are preferably formed or cut from angle steel and have their upper flanges lying in the same plane while their lower flanges lie in parallel planes. The front blade 1 is the longest while the intermediate blade 2 is the next longest and the rear blade 3 is the shortest. The plate 4 lies 40 transversely over the intermediate portions of the said blades and is riveted to the horizontal portions of each. The said plate 4 is provided upon its upper surface and at its 45 opposite ends with the metallic angle pieces 5 which serve as strengthening ribs or braces to add stiffness to the plate and may also be used as runners for transporting the implement when the same is turned upside down. The clevises 6 are attached to the horizontal portion of the blade 1 at points beyond the ends of the plate 4 and the draft chain 7 is connected at its ends with the said clevises. 50 The said chain 7 is provided at intervals throughout its length with the enlarged links

8 with any one of which a tree clevis (not shown) may be engaged.

As the implement is drawn along the surface of a road the blades will smooth off the high places in the road and fill the dirt into the ruts and depressions. The front blade 1 will deposit a windrow of dirt at the center, or near the center of the road. The intermediate blade 2, being shorter than the 60 blade 1, will leave a row of dirt just to one side of the first said row and the rear blade 3, being the shortest, will leave a row of dirt along side of the row made by the intermediate blade. Thus, the dirt is conveyed to 65 the middle of the road in several small windrows rather than a single large one as would be the case if the blades were all the same length. By providing the draft chain 7 with the enlarged links 8 the draft animals 70 may be attached to the implement so that the line of draft may be applied at any point along its length and the angle of inclination of the blade to the line of draft may be varied at will and the blades may be 75 caused to move with either end desired foremost. Thus, an adjustable and reversible drag is provided which will throw more or less earth according to its angle of inclination with relation to the line of draft and 80 may be operated in either direction at either side of the road by transferring the line of draft from one side of the middle of the implement to the other side thereof.

Having described our invention what we 85 claim as new and desire to secure by Letters Patent is:—

1. A drag comprising blades having vertical parallel portions, a plate lying transversely over the blades and rigidly connecting the same together and means for connecting the drag with a propelling means.

2. A drag comprising blades which differ in length and which have vertical parallel portions, a plate lying transversely over the 95 blades and connecting the same together and means for connecting the drag with a propelling means.

3. A drag comprising blades having vertical parallel portions, the forward blade being the longest and the blades gradually decreasing in length toward the rear of the implement, a plate lying over the blades and connecting the same together and means for connecting the drag with a propelling means.

4. A drag comprising blades formed of angular material having portions which lie in

the same plane and portions which lie in parallel planes, a plate lying over the blades and being attached to those portions thereof which lie in the same plane and means for connecting the drag with a propelling means.

5. A drag comprising blades, a plate lying transversely over the blades and connecting the same together, angle strips located at the end of said plate and means for connecting the drag with a propelling means.

10. A drag comprising blades, a plate connecting the same together, a draft chain

connected with the drag, beyond the end of the plate and having at intervals along its length enlarged links.

15

In testimony that we claim the foregoing as our own, we have hereto affixed our signatures in the presence of two witnesses.

FITCH H. BEACH.
FRED S. BEACH.
